UNITED STATES PATENT OFFICE.

RUSSELL C. JONES, OF BRONXVILLE, AND JOSEPH PRICE, OF NEW YORK, N. Y., ASSIGNEES TO THE GRISCOM-RUSSELL COMPANY, OF NEW YORK, N. Y., A CORPORATION OF DELAWARE.

HEAT EXCHANGER.

Application filed August 12, 1921. Serial No. 491,836.

To all whom it may concern:

Be it known that we, RUSSELL C. JONES and JOSEPH PRICE, both citizens of the United States, residing, respectively, at 5 Bronxville, Westchester County, New York State, and No. 2550 Briggs Avenue, New York city, Bronx County, State of New York, have invented certain new and useful Improvements in Heat Exchangers; and 10 we do hereby declare the following to be a full, clear, and exact description of the invention, such as will enable others skilled in the art to which it appertains to make and use the same.

15 The present invention relates to heat exchangers for oils or similar viscous liquids which become more fluid with rise of temperature.

In the use of oil as a fuel, burners are 20 employed that comprise passages through which the oil is pumped and mixed with air, and thence delivered into the combustion chamber in a finely atomized state. To secure complete atomization and perfect 25 combustion under the boilers it is necessary that the oil, as it passes to the burner, be in a limpid condition. Many crude oils used for fuel are of high viscosity at ordinary temperature but, however, become 30 sufficiently fluid at temperature of between 200° and 300° F. to be used and readily atomized in a burner. Accordingly in oil burning plants it is customary to preheat the fuel oil before it passes to the burners.

35 It is an object of this invention to provide a device for changing the temperature of any viscous liquid that becomes more fluid with increase in temperature, and more particularly in providing a heater for fuel 40 oil which receives the oil in a viscous state, heats it in the most efficient manner, and presents it to the burner in proper condition for atomization, the heater being compactly and conveniently constructed.

45 Heretofore the heating of fuel oil has been largely accomplished in heat exchangers of the type employed as feed water heaters, using steam as the heating medium. Such 50 heaters consist usually of a steam jacket or shell containing tubes for the passage of the feed water, the tubes usually being arranged in a number of groups connected to provide several "passes" of the water through the shell.

Experience has demonstrated that such 55 heaters, while practically operative, do not give as satisfactory results when used as oil heaters as they do when heating feed water, and it is the object of our present invention to provide an oil heater of the same 60 general type as the above described heat exchangers, but capable of heating fuel oil rapidly and efficiently in a manner impossible with heaters of present design. The 65 essential feature of our invention is the provision of a passage of varying cross sectional area for the oil through the heater, the portion of the passage of largest cross section being at the intake end of the passage where the cold oil is received from the 70 supply tank, the cross section of the passage being gradually reduced in accordance with the emerging condition of the oil.

This principle of our heat exchanger may 75 also be used to double advantage in refineries for condensing and cooling oil and in oil to oil heat exchangers, the cold oil being used as a medium for cooling the hot oil. In such cases the viscosity of both the 80 working fluid and the fluid acted upon vary with the temperature, and it is an object of our present invention to provide a heat exchanger in which an efficient transfer of heat is obtained when both mediums are 85 liquids of variable viscosity. When applied 90 to this purpose we provide passages of variable cross section for each of the two heat exchanging mediums, the area of each passage decreasing in the direction of decreasing viscosity of the liquid.

We have made an investigation of the 95 operation of these heat exchangers when used as oil heaters, and have ascertained some facts as to the nature of the action which takes place. The cold oil as it enters the 100 passage is exceedingly viscous, and its average temperature is much lower than that at the exterior of the containing tubes. Under these conditions the oil immediately adjacent to the walls of the tubes quickly 105 become warmed. However, owing to the viscosity of the cold oil at the center of the tubes, and its consequent resistance to movement, there are practically no convection currents established, or other form of 110 agitation, that would bring about a uniform heat distribution throughout the oil. The result is that the layer of oil adjacent to

the walls of the passage becomes heated to a temperature nearly equal to that at the exterior of the tubes, while the oil at the center of the tube remains for a time substantially at its original temperature and viscosity and is heated very gradually in its subsequent passage through the heater.

Due to this fact, the pressure head required per foot of travel through the first part of the fluid passage is materially greater than that necessary to maintain the flow through the latter portions of the passage. I have found that the necessary pressure head impressed over the first one-third of the length of the passage is fully one-half of the total pressure difference required between the inlet and outlet in passages having a uniform cross section throughout.

Conduction of heat to the inner portion of the oil column takes place but slowly. In oil to oil heat exchangers the entire volume of oil must therefore be brought into intimate contact with the heat transferring surface by passing it over baffles or forcing it through the fluid passage at a relatively high velocity for the purpose of causing a turbulent flow to insure uniform heat transfer throughout the entire volume. The provision of baffle arrangements is well adapted to certain situations but, as is well known in the art, such construction is subject to certain definite limitations and may be prohibitive in cost. On the other hand, it is not economical to employ an excessive pressure head to give the oil a high velocity through the heat transferring apparatus, particularly since the only pressure head available is sometimes a low gravity head. Applicant avoids these limitations by providing a heat transferring apparatus embodying a fluid passage of such construction that a high average velocity of flow throughout the apparatus may be obtained and yet in which the velocity of the most viscous portion of the fluid is relatively low and the total pressure difference required between the inlet and outlet is kept within the practical limits.

The pressure head is consumed uniformly along the length of the passage. This feature necessarily implies a uniform change in fluid pressure along the length of the passage, and increased agitation of the liquid during the portion of its passage in which it is more fluid.

Entirely analogous conditions exist when oil is being cooled. That portion immediately adjacent to the cooling surface becomes cooled to a temperature nearly equal to that of the surface of itself and a thin film of oil congeals about the cooling tubes, while the inner portion of the volume tends to remain at its original temperature. Thus in a heat exchanger for cooling oil or other viscous medium in which a viscous liquid is also employed as the cooling medium, the passage

for the hot oil should be of smaller area at the inlet and increase in the direction of flow, and that for the cooling oil should be greatest at the inlet and decrease in the direction of flow.

We have illustrated several forms of our invention in the accompanying drawings, in which:

Fig. 1 is a vertical sectional view of a fuel oil heater constructed with three passes;

Fig. 2 is a sectional view taken on line 2-2 of Fig. 1;

Fig. 3 is a view of the bottom head taken on line 3-3 of Fig. 1;

Fig. 4 is a sectional view taken on line 4-4 of Fig. 1, and showing the construction of the upper head;

Figs. 5 and 6 are views similar to Figs. 3 and 4 respectively, except that they show a heater having five passes.

Fig. 7 is a vertical section showing a modified form of apparatus adapted for installations in which both heat transferring mediums are viscous liquids;

Fig. 8 is a horizontal section taken on line 8-8 of Fig. 7;

Fig. 9 is a vertical sectional view showing another modified form of apparatus.

Fig. 10 is a horizontal section taken on line 10-10 of Fig. 9;

Fig. 11 is a vertical sectional view showing a still further modification.

Fig. 12 is a vertical sectional view showing an apparatus similar to that shown in Fig. 7, but illustrating a modified form of tube construction.

Fig. 13 is a horizontal sectional view on line 13-13 of Fig. 12.

Fig. 14 is a sectional view illustrating a type of apparatus similar to that shown in Fig. 9 but with a modified form of tube construction.

Fig. 15 is a transverse sectional view on line 15-15 of Fig. 14.

Referring to the drawings, particularly to Figs. 1 to 4, the heater consists of a number of parallel tubes 1 having their ends secured in tube plates 2, and mounted longitudinally within a shell 3. The shell and tube plates are welded together at 4. The heater is provided with a top head 5 and a bottom head 6 bolted to the tube plates 2 and containing separate compartments. In the three pass heaters shown in the drawing, the upper head 5 is provided with two compartments 7 and 8, as shown, and an outlet 9 for the oil, while the bottom head contains an inlet 10 opening into a compartment 11 and a second compartment 12. The ends of the tubes 1 extend through the plates 2 and open into the various compartments.

Referring to Fig. 2 it is seen that the tubes are divided into three groups 13, 14 and 15. Group 13 contains approximately

one-half of the total number of tubes, group 14 about one-third, and group 15 the remaining one-sixth. The oil inlet 10 (Fig. 1) opens into compartment 11, which compartment 5 is in communication with group 13 of the tubes. This group 13 opens at the upper head into compartment 7 which is also in communication with group 14, allowing the oil to flow through group 13 and back 10 through group 14. At the bottom head group 14 opens into compartment 12, which is in communication with group 15 also and allows the oil to flow up through group 15 into compartment 8, and from thence 15 through the outlet 9 to the burner. Thus the oil traverses the length of the heater three times, each time through a smaller group of tubes. Steam is admitted at the opening 16, encounters the baffle plate 17, 20 circulates about the tubes 1, and when condensed is drawn off through the drain 18.

The invention is in no wise limited to a three pass heater. Fig. 5 shows a five pass construction, and any convenient number 25 may be selected, depending upon the degree of uniformity of pressure drop desired along the passage. In Figs. 5 and 6 the oil would pass successively through groups 19, 20, 21, 22 and 23, each group after the first containing 30 a smaller number of tubes than the immediately preceding group. The arrangement of the compartments in the top and bottom heads would be as shown. That is the first compartment 11^a into which the inlet pipe 10^a leads is coextensive in area with the first group of tubes 19. The second compartment 7^a connects the group 19 with group 20 and is coextensive with both groups. The third compartment 12^a connects 35 groups 20 and 21. The fourth compartment 8^a connects groups 21 and 22 and the fifth compartment 12^b connects groups 22 and 23, while the sixth compartment 8^b forms an outlet chamber for the heater.

Figs. 7 and 8 illustrate a modified form 40 of the apparatus designed particularly for use where it is desired to cool hot oil by the use of cold oil as a cooling medium, but which is adapted for use in any installation 45 where it is desired to transfer heat between two viscous liquids. The apparatus here shown has three passes and comprises essentially a shell 3 and a plurality of longitudinal tubes supported within it in the manner previously described, the tubes serving as a 50 passage for one of the fluids and the space surrounding the tubes serving as a passage for the other fluid. Either the hot or cold liquid may be passed through the tubes. In Fig. 7 the tubes are shown as constituting 55 a path for the cooling liquid, the space surrounding the tubes constituting the path of the hot liquid.

The shell 3 is provided with an upper 60 head divided into chambers 26 and 27 and

a lower head comprising chambers 28 and 29. These heads are in direct communication with the tubes, the lower head being provided with an inlet 30 and the upper head with an outlet 31. At the upper end 70 of the shell 3 adjacent to outlet 31 there is provided an inlet 32 for the hot fluid, and at the other end of shell 3 adjacent to inlet 30 there is provided an outlet 33, the passages 32 and 33 being in direct communication with the space surrounding the tubes. 75

Group 13 of the tubes constitutes the first pass for the cold liquid and comprises the greatest number of tubes. Group 14 constitutes the second pass, having a lesser number of tubes than are contained in the first pass and within which the direction of flow is opposite to that in the first pass. Group 15 constitutes the last pass and contains the least number of tubes. 80

The cold liquid having a high velocity enters chamber 28 through the inlet 30. This chamber is in direct communication with the lower ends of the tubes in group 13, constituting the first pass through the shell, and allows the liquid to pass through this group of tubes and out into the chamber 26 at the other end of the shell. This chamber is in direct communication with the tubes in both groups 13 and 14. Consequently the liquid from the first pass discharges into chamber 26 and immediately flows into the open ends of the tubes of the second pass from whence it is discharged into chamber 29 at the lower end of the shell, chamber 29 is in direct 90 communication with the tubes of the second and third passes and serves to direct the discharge from the second pass into the open ends of the tubes constituting the third pass, from whence it is discharged into the small chamber 27 communicating with the outlet ends of these tubes and is discharged through outlet 31. Thus, the cross sectional area of the passage for the cold liquid decreases in the direction of decreasing viscosity which is also in the direction of its flow. 95

The space in the shell surrounding the tubes constitutes a passage for the hot liquid, this space being divided by partitions 115 34 and 35 into three compartments surrounding the tubes of the respective passes. The area of the space surrounding the tubes of the first pass is greatest, that surrounding the tubes of the second pass is smaller, 120 and that surrounding the tubes of the third pass is smallest. To obtain an efficient transfer of heat the counter flow principle is employed, the inlet 32 serving to admit the hot fluid to the pass of smallest cross sectional area. The hot fluid flows along in this space to the end of the shell, and then passes around the end of baffle 35, 125 which is made shorter than the length of the shell, into the space surrounding group 14 130

of the tubes constituting the second pass. The flow continues along tubes 14 to the opposite end of the shell where the fluid passes around the end of the baffle 34 through the space left for this purpose after which it again traverses the length of the shell through the space surrounding group 13 of the tubes and passes out at 33. Thus the area of the passage for the hot liquid also decreases in the direction of decreasing viscosity which in this case, however, is opposite to the direction of flow.

In Figs. 9 and 10 there is illustrated a modified form of apparatus having each pass arranged in a separate shell instead of being contained in a common shell as in Fig. 7. The tubes may serve as a passage either for the hot or cold fluids. For instance the cold medium may be admitted through the inlet 30 to the space surrounding group 13 of the tubes constituting the first pass and having the greatest area, in which case it would travel the length of the shell, through connecting pipes 36 into the space surrounding the tubes of the second pass, along the length of this second pass into the third pass by means of a connecting tube 37, and from thence to the outlet 31. The hot fluid is admitted at inlet 32 into the tubes of the pass of smallest section, issues from them through connecting pipe 38 into the tubes of the second pass, and from thence through the second pass into the space of largest area by means of connecting tube 39, from whence it issues through the outlet 33. In this form of apparatus each of the fluid passages decreases in the direction of decreasing viscosity, or increases in the direction of increasing viscosity as the case may be.

In Fig. 11 there is shown a still further modification of the type of apparatus adapted to transfer heat between two viscous liquids, in which the various passes are contained in separate shells. In this design common heads 40 are employed for the tubes of the various passes, with chambers coextensive with the heads for directing the flow of liquid through the tubes. The tubes are however arranged in separate groups and separate cylindrical shells surround each group, the separate shells being connected by pipes 36 and 37. The cold medium may be admitted through inlet 30 into the shell surrounding the tubes of the first pass, from whence it makes its way through the successive passes by means of the connecting tubes 36 and 37 and finally issues from the outlet 31 substantially as in the apparatus shown in Fig. 9. The hot medium is admitted to the chamber 27 which is in communication with the tubes of the pass having the smallest cross sectional area. The liquid is discharged from the first pass into the chamber 29, which is in communication with both the pass of smallest area and that of

the next largest area. The discharge from the second pass is received in chamber 26 which communicates also with the pass of the largest sectional area and serves to admit the fluid to this latter pass, from whence it is subsequently discharged through chamber 28 and the outlet 33.

Figs. 12 to 15 show a modification embodying a somewhat different type of tube construction. Figs. 12 and 13 show an apparatus in which the elements are contained within a single shell 3 having a lower head 6 provided with the usual inlet passage 30 and outlet passage 31 for the fluid being acted upon. The tubes constituting the fluid passage are of an inverted U-shape, the open ends of the tubes being expanded or otherwise secured in a tube sheet 2. Three groups of tubes are provided for obtaining a fluid passage of variable cross section, the group 13 having the greatest number of tubes and consequently being of the largest cross section. The fluid admitted at the inlet 30 passes up through the tube 13 and subsequently traverses the length of shell in the reverse direction after passing around the bends at the upper end of the tube elements. At the bottom of the shell the fluid is discharged into a chamber 12^a which is also in communication with the inlet end of the tubes comprising the group 14. The entire volume of the liquid admitted thus traverses each of the three groups of tubes passing up and down the length of the shell during its passage through each group, and is subsequently discharged from the outlet 31. Cooling liquid is admitted to the shell through the inlet opening 32 and by means of baffles 41 and 41^a is directed up and down the length of shell substantially in conformity with the path followed by the fluid being acted upon, except that its flow is in the reverse direction, and is subsequently discharged at the outlet 33. The baffles 41 are preferably supported by the tube sheet 2, while the intermediate baffles 41^a are secured to the removable upper head 42 and extend down to the interior of the shell. This type of tube construction is particularly valuable in that a damaged tube element may be withdrawn by simply removing the upper head 42, loosening the two ends of the tube element which are secured in the tube sheet, and plugging up the holes thus formed.

Figs. 13 and 14 disclose a similar type of tube construction, the various groups of tubes being enclosed in individual shells. The arrows indicate that the fluid being cooled is passed through the tubes. Each shell is provided with a removable head 42 for the purpose of affording ready access to the tube elements and contains a central baffle 41 extending upwardly from the tube sheet 2 and serving to direct the flow of the working fluid along the length of the tubes.

The modification illustrated in Figs. 12 to 15 afford a fluid passage of graduated area divided into three sections of equal length, each section having a different area. Since 5 the fluid in traversing each group of tubes passes up and down the length of the shell, an apparatus comprising three groups as shown constitutes a six-pass cooler. It is obvious that any number of passes desired 10 may be built into a given apparatus. The apparatus as shown is designed as an oil to oil heat exchanger, and the sectional area of the passage surrounding the tubes change in about the same proportion as does the passage within the tubes.

The transfer of heat by a liquid depends largely on the temperature difference between the liquid and its immediate surroundings, and upon the agitation in the liquid 20 itself, which mixes the liquid at the walls of the container with the liquid from the interior and secures a uniform heat distribution.

The common practice is to build heaters 25 or coolers of this type with the passage for the liquid to be acted upon of constant cross sectional area throughout. This type of construction necessitates the same fluid velocity in all parts of the passage. If the 30 liquid is viscous at the lower temperature, this velocity is determined by the rate at which the viscous liquid can be fed through the passage. Furthermore, most of the pressure head is consumed in that portion of the 35 passage at which the liquid is most viscous, which results in a retarded flow of the liquid during that part of its path in which it is more fluid, and consequently an absence of the agitation so necessary to efficient transfer 40 of heat.

With our improved heat exchanger the viscous oil moves slowly through the pass of larger area but its velocity increases materially upon entering the passes of smaller 45 cross section. The change in cross sectional area of the fluid passages is proportional to the changing viscosity of the liquid so that a substantially uniform pressure drop per unit of length will be obtained throughout 50 the apparatus. In this manner a high average velocity is maintained with a correspondingly high heat transfer efficiency.

If desired twisted metal strips 25 as shown in Fig. 1 may be inserted in the tubes and 55 fastened at the ends to serve as an agitator. These strips are used only in the last pass, or last several passes, in which portion of the passages the oil is relatively limpid, where an agitation of the oil will be effected 60 without adding undue resistance to the feed.

We have described the apparatus shown in Figs. 1 to 6 as an oil heater employing steam in the shell as the heating medium, but it will be understood that the apparatus 65 may be used to advantage as an oil cooler

by reversing the direction of the flow of the oil through the tubes and using a cooling fluid in the shell. It will be also understood that our invention is not limited to the details of construction of the various modifications here described, but that the structural features of the several designs may be variously modified for convenience of manufacture and to suit different conditions.

We claim:—

1. Apparatus for heating a viscous liquid, comprising a shell, a plurality of metal tubes arranged longitudinally within said shell and constituting a passage for the liquid, said shell having an inlet for steam and a drain for removing the residual water, means at the ends of the shell for effecting the division of the tubes into successive groups connected in series, each of said successive groups containing a fewer number of tubes than the preceding group, thereby decreasing the cross sectional area of the passage in the direction of decreasing viscosity of the liquid.

2. In an apparatus for heating a viscous liquid, the combination of a support, a plurality of metal tubes arranged in parallelism therein and constituting a passage for the liquid, means for circulating a heating fluid around the exterior of said tubes, means at the ends of the tubes for effecting the division of the tubes into successive groups connected in series, each of said successive groups containing a fewer number of tubes than the preceding group, thereby decreasing the cross sectional area of said passage in the direction of decreasing viscosity of the liquid, and twisted metal agitator strips inserted into the tubes of the last groups.

3. An apparatus for transferring heat between two liquids whose viscosity varies with change in temperature, a passageway for each of said liquids in heat exchanging proximity to the other, the cross sectional area of each said passageway varying in the direction of the flow of the liquid therethrough, and means for directing liquids at different temperatures through said passageways in such direction that the passageway of the liquid losing its heat increases in area and the passageway of the liquid absorbing heat decreases in area.

4. An apparatus for transferring heat between two liquids whose viscosity varies with change in temperature, a passageway for one of said liquids comprising a plurality of parallel tubes, a passageway for the other liquid surrounding said tubes, the cross sectional area of each said passageway varying in the direction of the flow of the liquid therethrough, and means for directing liquids at different temperatures through said passageways in such direction that the passageway of the liquid losing its

heat increases in area and the passageway of the liquid absorbing heat decreases in area.

5. In an apparatus for transferring heat between two liquids whose viscosity varies with change in temperature, a plurality of parallel tubes constituting a passage for one of said liquids, means for effecting a division of said tubes into successive groups 10 connected in series, each of said successive groups containing a fewer number of tubes than the preceding group, and a passage for the other of said liquids comprising a compartment surrounding each group of tubes, 15 said compartments being connected in series and each successive compartment having a smaller area than the preceding one.

6. The method of changing the temperature of a viscous liquid comprising passing 20 said liquid through a passage whose cross-

sectional area varies as the viscosity of the liquid varies and bringing heat transferring fluid into heat exchanging relation with said viscous liquid.

7. The method of changing the temperature of a viscous liquid which comprises directing the liquid through a passage whose cross-sectional area diminishes as the viscosity of the liquid diminishes whereby the velocity of flow is greater in that portion of the passage where the liquid is most fluid and bringing a heat exchanging medium into heat transferring relation with the liquid in said passage for changing the temperature thereof.

35 In testimony whereof we affix our signatures.

JOSEPH PRICE.
